Primary Examiner—A. Hugo Word**Assistant Examiner**—Doris V. Coles**Attorney, Agent, or Firm**—Rodgers & Rodgers**[57] CLAIM**

The ornamental design for a fishing lure, as shown.

DESCRIPTION

FIG. 1 is a perspective view of a fishing lure showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken line showing of environment in FIGS. 1,2,5 and 6 is for illustrative purposes only and forms no part of the claimed design.

FIG. 1

FIG. 2

FIG. 3

FIG. 4

FIG. 5

FIG. 6
